TELEPHONE ANSWERING SYSTEM

Paul Henry Rowe, Los Angeles, Calif.

Application August 30, 1937, Serial No. 161,616

24 Claims. (Cl. 179—6)

This invention relates to automatic devices for answering telephone calls, and is particularly useful in connection with telephones that are unattended part of the time.

5 A broad object of the invention is to generally increase the efficiency and field of usefulness of automatic telephone answering and message-recording systems.

This is a continuation in part of my copending 10 application Serial No. 661,741, filed March 20, 1933 on Telephonographs, issued Sept. 7, 1937, as Patent No. 2,092,024.

15 The single figure of the drawing is a schematic diagram of a complete telephone answering and message-recording system in accordance with my invention.

20 My system comprises, as its essential elements, a first record device adapted to deliver a pre-determined speech over a telephone in response to a call on the telephone, informing the calling party that the person called is out and that a message will be recorded, a recording medium for recording a conversation received over the telephone line from the calling party, various 25 relays, amplifiers and other circuit elements for automatically associating the record devices with the telephone line in operative relation, and additional apparatus whereby the absent subscriber may call his own telephone and have a message 30 that has been left for him in his absence relayed to him over the same telephone line.

35 Referring to the drawing, the speech delivering device is shown as comprising an endless telegraphone wire 1 extending about a pair of drums 2 and 3, respectively, and adapted to be moved from one drum to the other by a small auxiliary drum 4 driven by a motor 5, the telegraphone wire 1 being wound about the auxiliary drum 4 or being otherwise in frictional engagement with it. The shaft of the motor 5 also has a worm 6 thereon adapted to rotate a wormwheel 7 connected to a cam 8 which controls a pair of contacts 9. Positioned adjacent the wire 1 at one of its points of passage between the drums 2 and 45 3 are three control magnets 10, 11 and 12, respectively, these magnets having the ends of their cores positioned adjacent the moving wire 1. The motor 5 is adapted to shift the wire in such a direction as to move it from right to left 50 successively past the magnets 12, 11 and 10. The magnet 12 is a reproducing magnet adapted to have sound currents induced in its winding in response to movement therewith of a portion of the wire 1 having a magnetic recording thereon.

The magnet 11 is a wiping or erasing magnet adapted to be energized by a high frequency current for erasing a message recorded on the wire, and thereby preparing it for the recording of a new message. The magnet 10 is a recording 5 magnet adapted to record a message magnetically on the wire 1 moving therewith when the magnet is energized with voice current.

The apparatus for recording a message received over the telephone line from a calling 10 party comprises a record medium, shown in the drawing as a telegraphone wire 15, of substantial length which is initially wound upon a drum 16 and adapted to be unwound therefrom onto a second drum 17. The drums 16 and 17 are 15 adapted to be rotated independently by separate motors 18 and 19, respectively. The motor 19 functions to wind the wire onto drum 17 from drum 16. The direction of movement can be reversed to unwind wire from drum 17 onto drum 20 16 by energizing the motor 18. Positioned adjacent the wire 15 are a reproducing magnet 40, a wiper magnet 41, and a recording magnet 42 similar to magnets 12, 11 and 10, respectively, associated with the telegraphone wire 1. 25

The drum 16 has associated therewith an overwind switch 20 comprising a movable contact 21, a back contact 22 and a front contact 23 for opening and closing certain circuits in response to winding of all of the wire 15 onto drum 16. 30 Drum 17 likewise has associated therewith an overwind switch 24 having a movable contact 25, a back contact 26 and a front contact 27 which are actuated when the drum 17 fills with the wire 15. 35

The system disclosed in the drawing also includes a pair of amplifying tubes 28 and 29 for amplifying the sound currents received and transmitted, a hybrid coil 30, balancing network 31 and pad 32 for associating the input and output circuits of the vacuum tubes 29 and 28 with the telephone line for 2-way communication thereover, in accordance with standard telephone practice. The telephone line proper is not shown in the drawing but is adapted to be connected by the usual plug to a jack 33 having a tip conductor 35 and a ring conductor 34 which are permanently connected to the pad 32 through a condenser 36. The vacuum tubes 28 and 29, as 40 disclosed in the drawing, are of the pentode type, each having a control grid, a screen grid and a suppressor grid in accordance with well-known practice. Obviously other types of 45 vacuum tubes can be employed. 50 55

As is well-known in the telephone art, the hybrid coil 30 in combination with the balancing network 31 makes possible application of sound currents from the output tube 28 to the telephone line, and application of sound currents from the telephone line to the input tube 29, while preventing currents in the output circuit of tube 28 from being applied to the input circuit of tube 29.

10 The motors 5, 18 and 19 for driving the telephone wires are adapted to be energized from any suitable source of current such as the usual alternating current power supply indicated schematically at 37. The system also includes various relays and control devices, some of which are adapted to be operated from a source of direct current and for this purpose a battery 38 is provided. To supply high frequency current to energize the wiper magnets 11 and 41, low voltage current to energize the cathodes of the tubes 28 and 29, high voltage current to energize the plates and screen grids of tubes 28 and 29, and biasing potential for the grids of tubes 28 and 29, a power supply unit 43 is provided, this unit 20 including a filament current supply unit 44, a plate current and grid biasing voltage supply unit 45 and a high frequency generator 46, all of which are adapted to be energized from the alternating current source 37 over input conductors 25 47 and 48, respectively.

The operation of the various elements described, together with the functions and mode of operation of the various relays and other circuit elements not yet mentioned in detail, will 35 now be explained by following through the operations of the system.

The system is adapted to be used in connection with a standard telephone line employing what is known as divided ringing. Such lines 40 are commonly employed on party lines. Thus the line is so arranged that by calling either of two distinct numbers the ringing current may be sent out over either the tip or the ring side of the line, returning through ground, depending upon 45 which number is called. This is the same circuit as far as the telephone plant is concerned as the conventional two-party line except that in this instance both sides of the line are employed by the same subscriber. One of the numbers 50 is published in the directory and all parties desiring to communicate with the subscriber call on that number. In the drawing, if the published number is called, ringing current is applied to the ring side 34 of the line. The other number 55 is not published in the directory but is merely used to effect remote control of my system from a distant telephone by the subscriber himself in a manner to be described later.

Now let it be assumed that some one calls the 60 subscriber's published number, thereby causing ringing current to be applied over the ring side 34 of the line through a condenser 50 and winding of a relay 51 to ground 49 thereby energizing relay 51 and causing the latter to close its normally opened contacts 52. This completes a circuit from pole 53 of battery 38 through contacts 52, a winding 54 of a solenoid relay 55, thence over a conductor 56 and the back contacts 26 and movable contact 25 of switch 24 associated 70 with the drum 17 back over a conductor 57 to the other pole 58 of battery 38, thereby energizing the winding 54 causing the latter to attract the solenoid core 59 and move a switch member 60 mechanically connected thereto to the left. 75 The lower end of the member 60 slips past the

left end of a latch member 61 and is left locked in said position following deenergizing of winding 54. Member 60 is permanently connected to one conductor 62 extending from the source of alternating current 37; therefore movement of 5 the member 60 to the left completes a circuit from conductor 62 over a contact 63 and armature 64 of a relay 65, a back contact 66 associated with armature 64, and a conductor 67 to motor 19 and thence over a conductor 68 to the other 10 side of alternating current source 37, thereby energizing the motor 19 to rotate the drum 17 and move the telephone wire 18 to the left past the magnets associated therewith.

The movement of the member 60 of the solenoid relay 55 to the left also completes a circuit between member 60 and a contact 69 to the input conductor 47 of the power supply unit 43, the other input conductor 48 of which is permanently connected to the other side of the source 20 37, thereby energizing the power supply units 44, 45 and 46 to cause them to supply filament current, plate current and grid biasing voltage to the tubes 28 and 29 and high frequency current for the erasing magnets 41 and 11. The output side of the filament current supply unit 44 is permanently connected by a pair of conductors 70 to the filaments of tubes 28 and 29 and the grid biasing voltage output terminal of unit 45 is connected by a conductor 73 permanently 30 to the control grids of tubes 28 and 29 whereas the plate supply output terminal of unit 46 is connected through a conductor 71 to the anodes and screen grids of tubes 28 and 29 through a relay 72. Return connection from the plate current and grid biasing voltage supply unit 45 to the filament circuits of the tubes is effected by a conductor 74 between units 44 and 45.

The filaments of tubes 28 and 29 require a few seconds to heat up and during the heating 40 period the plate current flowing through relay 72 gradually increases. This slowly energizes the relay causing it first to close its contacts 75 to complete a direct current path, through contacts 75 and the normally closed contacts 76 in shunt to the condenser 36. Thereafter as the plate current reaches full normal value the relay is further energized to open contact 76 and break the direct current path in shunt to condenser 36. The net result is that condenser 36 is short-circuited for a very short interval of time, thereby closing a direct current path of relatively low resistance between the ring and tip sides of the telephone line through the pad 32, the hybrid coil 30 and the balancing network 31 to trip the usual relay in the telephone plant and interrupt the ringing current and leave the line in condition for conversation. It will be understood that voice currents pass readily through the condenser 36 and into the hybrid coil 30 and the balancing network 31.

The movement of the solenoid relay element 60 to the left also carried an insulating element 77 mechanically attached thereto to the left to close a contact 78 on a contact 79 and complete a circuit from the pole 53 of battery 38 over a conductor 80, contact 78, contact 79, a conductor 81 through the winding of a relay 82 back over a conductor 83 through a pair of contacts 84 on a ratchet switch 85 to conductor 57, which is permanently connected to pole 58 of battery 38, thereby energizing relay 82 and causing its armature 87 to open its back contact 88 and close on its front contact 89 and complete a circuit between a primary winding 90 of a transformer 75

91 and the reproducing magnet 12 associated with the telephone wire 1. The secondary winding 92 of transformer 91 is connected through a potentiometer 93 to the control grid circuit of vacuum tube 28. The plate circuit of output tube 28 is permanently connected in transmitting relation with the telephone line through the hybrid coil 30.

The movement of the bar 77 of the solenoid relay 55 to the left is sufficient to move contact 78 a substantial distance to the left and contact 79 is mechanically connected by an insulating member 94 to an auxiliary contact 95. As has previously been described, relay 82 was energized 15 in response to closure of contacts 78 and 79. At the same time a relay 97 having its winding connected in shunt to winding of relay 82 was energized. Energization of relay 97 closed a pair of contacts 98 thereon. The closure of contacts 96, 20 95 and the contacts 98 completed an energizing circuit for the motor 5 on the answering telephone. This circuit may be traced over conductor 68 from one side of the A. C. source 37 through the motor 5, thence over a conductor 99, 25 the contacts 98 of relay 97, a conductor 100, the contacts 95 and 96 and the contact 63 and member 60 of the solenoid relay 55 and back over conductor 62 to the other side of source 37.

The foregoing operations all take place within 30 a very few seconds following the institution of the telephone call, at the end of which time the telephone motors 5 and 19 have accelerated to operating speed and the telephone wire 1 passing the reproducing coil 12 cooperates there- 35 with to transmit through the transformer 91, vacuum tube 28 and the hybrid coil 30 to the telephone line conductors a message which has been previously recorded on the telephone wire 1, which message will be heard by the calling party at the other end of the telephone line. 40 This message may be worded as follows: "You are connected with subscriber 'A'. There is no one here at the moment. However, the recording device to which you are listening will take 45 down your message. Please be sure to leave your name and address. Go ahead, please." The calling party may now speak his message which comes in over the telephone line and is applied over conductors 103 leading from the 50 hybrid coil 30 through a filter 104, a transformer 105 and a potentiometer 106 to the control grid circuit of vacuum tube 29. These voice currents are amplified by tube 29 and applied from the plate circuit of the tube through a transformer 55 107, conductors 108 and 109 and closed contacts 110 and 110a of the relay 97 (previously actuated as described) to the recording coil 42 associated with the moving telephone wire 15. The message is thereafter recorded on the wire 60 15. The operation of relay 97, also moves an armature 112 thereon out of engagement with a back contact 113 into engagement with a front contact 114 thereby completing a circuit from the high frequency generator 46 over conductors 115, 65 116, armature 112 and front contacts 114 to the erasing coil 41, thereby automatically erasing any previous message that might be on the wire 15 prior to the recording thereon of a message by the recording coil 42.

70 The circuit will remain in the condition last described until the telephone wire 1 has about completed a cycle, at which time the cam 8, actuated from the motor 5 through the worm 6 and wormwheel 7, closes the contacts 9 thereby completing a circuit for energizing a trip magnet 117

associated with the solenoid relay 55 which magnet when energized depresses the latch 61 to release the solenoid relay 55 and permit it to assume normal position. The energizing circuit for magnet 117 may be traced from pole 53 of battery 38 over conductor 80, contacts 78 and 79 of the solenoid relay, conductor 81, magnet 117, conductor 118, contacts 9 and conductor 57 back to pole 58 of battery 38.

The restoration of the solenoid relay 55 to 10 normal position opens the power supply contact 63 thereby causing both telephone motors 5 and 19 to stop. However, the telephone mechanism has sufficient inertia to continue in motion after the power supply to the motors is 15 cut off long enough to carry the cam 8 past the contacts 9, thereby reopening those contacts. This completes a cycle of movement of the telephone wire 1, leaving it in its original position. The opening of contacts 9 and the various 20 contacts associated with the solenoid relay 55, deenergizes the entire system and restores it to original condition except for the fact that a certain portion of the telephone wire 15 which may bear a message left by a calling party will 25 be wound upon the drum 17. In response to succeeding calls the circuit will be actuated in exactly the same manner already described, to record succeeding messages on successive portions of the telephone wire 15. The number of messages 30 which the machine will take down is determined by the length of the telephone wire 15. If a sufficient length of wire 15 is initially wound upon the drum 16 to run, say, twenty times as long as the time required to complete a cycle of 35 movement of the answering telephone wire 1, then it will be obvious that the machine can record twenty successive messages before the telephone wire 15 is completely filled.

If the subscriber now returns home, he may 40 reproduce the messages recorded on the wire 15 in any conventional manner. However, one of the novel features of this invention is that the subscriber need not return home in order to hear the messages which are recorded on the telephone wire 15. Instead he can have these messages reproduced for him over the telephone line by a procedure next to be described.

Assume that the subscriber is at a distant telephone and calls his own unpublished telephone 50 number. This causes ringing current to be sent out over the tip side 35 of the line through a condenser 125 and a relay 126 and thence to ground 49. Relay 126 is provided with an armature 127, the movement of which is controlled by a dash 55 pot 128 so that it rises slowly. The end of the armature 127 is adapted to engage an insulated arm 130 and rotate the latter in a counterclockwise direction about its lower end 130a, which is pivotally mounted, to cause a shoulder 135 on 60 the arm 130 to engage a pair of contacts 131 and close those contacts. The relay is so adjusted that the first impulse of ringing current through the relay 126 lifts the armature 127 and the arm 130 sufficiently to close the contacts 131 65 but does not close the armature 127 on contact 129. However, the closure of contacts 131 performs no function under the condition described.

Continued application of ringing current to relay 126 lifts the armature 127 higher and higher, 70 the dash pot 128 being so arranged that it will allow the armature 127 to drop back between ringing impulses a fraction of the distance it was lifted by the previous ringing impulse. After several such impulses the armature 127 will be 75

carried high enough to disengage the arm 130 due to the counterclockwise rotation of the latter, thereby permitting restoration of the arm 130 to normal position, and opening contacts 131. The gradual upward movement of the armature 127 finally closes the armature on contact 129 thereby applying current from battery 38 to winding 136 of solenoid relay 55, the circuit extending from pole 53 of battery 38 through armature 127, contact 129, winding 136, a conductor 137, back contact 22 and movable contact 21 of switch 20 associated with telephone drum 16 and thence back over conductor 57 to pole 58 of battery 38.

The energization of winding 36 of solenoid relay 55 moves the member 60 to the right to complete a circuit from the alternating current source 37, conductor 62, the member 60 and a contact 139 to the power supply unit 43, energizing the latter. At the same time contact of member 60 on a contact 140 completes an energizing circuit over a conductor 41 through motor 18 to conductor 68 and the other side of the source 37, thereby starting motor 18 to wind the telephone wire 15 backwards off of the drum 17 and onto drum 16.

The actuation of the member 60 on solenoid relay 55 to the right (in which position it is retained by the latch 61) also causes a detent 141 on the right end of bar 71 to engage and rotate a ratchet wheel 142 carrying a cam 143 which actuates the contacts 84 thereon. The ratchet wheel 142 has six teeth and is attached to a cam 143 having three points or lobes which actuate the contacts 84 so that a movement of the ratchet wheel 142 through a sixth of a revolution opens the contacts 84 if they were previously closed and closes the contacts 84 if they were previously opened. These contacts 84 are normally closed and remain so as long as calls come in over the ring side of the line only to actuate the solenoid relay 55 from normal position into left position and back to normal position because with the ratchet wheel 142 in the position shown in the drawing, the movement of the pawl 141 on bar 71 to the left is not sufficient to engage the next tooth. However, when the subscriber now calls in over the tip side of the line to reverse the direction of the telephone wire 15 by energizing motor 18 in the manner described, the pawl 141 moves far enough to the right to engage a tooth on the ratchet wheel 142 and shift the latter far enough to open contacts 84. This opens the energizing circuits for relays 82 and 97 so that those relays cannot operate despite the closure of contacts 78 and 137 on the solenoid relay 55. Since the relay 97 is not operated, the front contact 114 of that relay is opened and the erasing magnet 41 associated with telephone wire 15 is not energized. Therefore the messages on the wire are not erased as the wire is rewound on the drum 16. When all the wire is rewound onto drum 16 the switch 20 is actuated to open contact 21 of contact 22 and close it on contact 23, thereby completing a circuit from battery 38 over conductor 57, contacts 21 and 23 of switch 20, through conductor 118 and latch magnet 117 to release the latch 61, thereby restoring the relay 55 to normal position and stopping the motor 18.

The subscriber has now completed one operation, namely, the rewinding of the record wire 15 onto drum 16. He thereupon hangs up and then calls his published number, thereby applying ringing current to the ring side 34 of the line, energizing relay 51 to actuate the solenoid relay 55 into left position, thereby starting the motor 19

over the circuit previously traced to wind the telephone wire 15 from the drum 16 onto drum 17. However, since the contacts 84 on the ratchet switch 85 are still open, relays 82 and 97 do not operate and since relay 97 does not operate, the energizing circuit for the motor 5 is not completed and the telephone wire 1 remains stationary. Furthermore since the relay 82 is not energized, the reproducing magnet 40, associated with telephone wire 15, is connected through the back contact 88 and the armature 87 of relay 82 to the primary winding 90 of transformer 91 which feeds into the output tube 28 connected with the line. Therefore as the telephone wire 15 runs past the reproducing magnet 40 the messages recorded thereon are relayed over the telephone line to the listening subscriber.

When the end of the series of messages is reached, the subscriber hangs up and again calls his unpublished number, thereby ringing back 20 on the tip side 35 of the line to energize the magnet 126 in the manner previously described to again energize the motor 18 and rewind the telephone wire 15 back onto the drum 16. The movement of the ratchet pawl 141 to the right again actuates the ratchet wheel 142 and cam 143 to again close contacts 84, thereby energizing relays 82 and 97, and the closure of armature 112 on front contact 114 of relay 97 applies high frequency current to the erasing magnet 41 so that all the messages on the wire 15 are erased as the wire is rewound on drum 16. When the wire is all rewound onto drum 16, switch 20 is actuated to close contacts 21 and 23 thereon to energize the latch magnet 117 and restore the solenoid relay 55 to normal position.

This carries the system through a complete cycle of operations and leaves it ready to take down incoming messages in the manner previously described.

The system, as described so far, provides for the answering of telephone calls and the recording of messages left by calling parties. It also provides means whereby the subscriber can call his own station from a distant point, have the recorded messages repeated to him, and then erase all the recorded messages, leaving the apparatus in condition to receive a new set of messages.

In accordance with my invention, I further provide for the changing of the message on the telephone wire 1 by the subscriber from a distant point. Let it be assumed that the usual message stating that there is no one present to answer the telephone and requesting that the calling parties dictate their messages, is recorded on the telephone wire 1. Assume then that the subscriber is suddenly required to leave the city and will be unable to take care of any business which the calling parties may desire to transact with him until his return. Assume further that the subscriber is unable to return to his home or office where the recording apparatus is located in order to record this information on the telephone wire 1. He can, however, change the message in my system from a remote point by the following procedure:

He uses the nearest available telephone and listens to the messages on the telephone wire 15 in the manner previously described by first 70 calling his unpublished number to rewind wire 15 onto drum 16, and then calling his published number to wind wire 15 onto drum 16 while reproducing the messages thereon. When the end of the series of messages is reached, he hangs up 75

and again calls his unpublished number, thereby again applying ringing current to the tip side of his line to energize relay 126 long enough to close contacts 131, but he hangs up his receiver to stop the ringing current before the relay 126 has time to close its armature 127 on contact 129. Relay 126 therefore releases after momentarily closing contacts 131.

Now, as can be seen from the drawing, the contacts 132 are open when the solenoid relay 55 is actuated into left position, by virtue of the fact that the movable contact of the pair of contacts 132 is connected to the insulating bar 94. By virtue of the fact that contacts 132 were open at the time contacts 131 were closed (in response to the short application of ringing current over the tip side of the line) current, instead of being supplied directly from pole 58 of battery 38, over conductor 57 and contacts 132 to contacts 131 20 and thence through magnet 117 to the other pole of the battery, was supplied from conductor 57 through the winding of relay 65 to contacts 131 thereby operating relay 65 as well as magnet 117. When operated, relay 65 is locked up by a latch 145. The operation of relay 65 broke contact of armature 64 with back contact 66 (stopping motor 19) and closed the armature on a front contact 147. The energization of magnet 117 of course released solenoid relay 55.

30 The subscriber next calls his published number, thereby applying ringing current to the ring side 34 of the line, actuating the solenoid relay 55 to the left in the manner previously described, and applying power from the A. C. source 35 37 over conductor 62 through the solenoid relay member 60, contact 63, armature 64 and front contact 147 of relay 65, and conductor 148 to motor 5, and thence back over conductor 68 to the other side of source 37, thereby setting the 40 telephone wire 1 in motion. However the telephone motor 19 remains idle since its operating circuit is open at contact 66 of relay 65. Since the sequence of operations described will have left the contacts 84 of ratchet switch 85 in open condition, relays 97 and 82 will be deenergized and the recording coil 10, associated with telephone wire 1, will be connected to the secondary winding 149 of transformer 107 through the back contact 150 and armature 110 45 of relay 97 so that any message repeated over the telephone line by the subscriber from a distant point will be transmitted through tube 29 and transformer 107 to the recording magnet 10. At the same time the erasing coil 11 is connected to the source of high frequency current 46 through the back contact 113 and armature 112 of relay 97 so that any prior message on the wire 1 will be erased by the magnet 11 prior to the recording thereon of a new message by the 50 recording magnet 10.

The subscriber now dictates the information he wishes recorded on the answering telephone wire 1 in place of the message previously recorded.

55 When the wire 1 has completed its cycle of movement and the contacts 9 are closed by the cam 8 to actuate the latch magnet 117 and stop the mechanism in the manner previously described, the subscriber hangs up and then calls 60 his unpublished number again, thereby applying ringing current to the tip side of the line long enough to energize motor 18 and rewind the telephone wire 15 onto the drum 16 in the manner previously described.

70 The movement of the bar 77 of the solenoid

relay 55 to the right in response to ringing current received over the tip side of the line, closes contact 137 on a contact 138, applying current from pole 58 of battery 38 over conductor 80, contacts 78, 137 and 138 of solenoid relay 55, over a conductor 151, through a magnet 148 and back to the other pole 58 of battery 38, thereby energizing the magnet 148, which pulls the latch 145 and releases the armature 64 of relay 65. Motor 18 continues to run until contacts 23 and 10 21 of the overwind switch 20 are closed to trip the magnet 117, releasing the solenoid relay 55 and restoring the system to normal condition ready to assume normal operation with the new answering record on the telephone wire 1. 15

The contacts 25 and 26 of the winding switch 24 associated with drum 17 open in response to filling of the drum 27 with the wire 15 to open the circuit to winding 54 of the solenoid relay 55 and prevent any possibility of starting the 20 motor 18 when all of the wire 15 is wound on drum 17. The contacts 23 and 21 of switch 20 function in a similar manner to prevent operation of the motor 18 when all the wire is wound on drum 16. 25

Although my invention has been explained by describing in detail a specific circuit for practicing the invention, it is to be understood that many changes and refinements can be made in the particular circuit details shown without departing from the invention, and the latter is to be limited only to the extent set forth in the appended claims. 30

I claim:

1. In an automatic telephone answering and message recording system, means for delivering a predetermined message over a telephone line to a calling party, means for recording a message received over the telephone line from a calling party, and means for connecting said message delivering means in transmitting relation to said telephone line and simultaneously connecting said message recording means in receiving relation with said telephone line, including means for preventing local intercommunication between said message transmitting and message receiving means. 40

2. In an automatic telephone answering and message recording system for use in combination with a telephone line equipped with automatic ringing apparatus which is adapted to be tripped in response to closure of a direct current path across said line; message recording apparatus, a vacuum tube amplifier, power supply means for energizing said amplifier, means including said amplifier for operatively connecting said recording apparatus to said line, means responsive to ringing current on said telephone line for energizing said power supply means, and means responsive to current flow from said power supply means through said amplifier for closing a direct current path across said line when said amplifier is partly energized and for opening said direct current path when said amplifier is deenergized and is fully energized, whereby the ringing apparatus on the telephone line is tripped and thereafter the telephone line restored to normal condition in response to ringing current on the line. 50

3. In an automatic telephone answering and message recording system, a device for delivering a word message, a message recording device, and means for energizing said message delivering and message recording devices and operatively connecting them to the telephone line in response 70 75

to ringing current on said line, said last mentioned means comprising an A. C. relay operable in response to ringing currents on said line and a self-locking relay adapted to operate and lock 5 up in response to operation of said A. C. relay, with means for releasing said self-locking relay after a predetermined lapse of time.

4. In a call answering and message recording system for use in connection with a metallic 10 telephone line equipped for divided ringing, means for recording and reproducing a message, and means selectively responsive to ringing current applied successively to the two sides of said line in predetermined different sequences for selectively conditioning said recording and reproducing means either to record a message transmitted over said line or to transmit a recorded message over said line.

5. A system as described in claim 4 with means 20 for signaling to a calling party when said recording and reproducing means is conditioned to record a message transmitted over said line.

6. In a telephone answering and message recording system for use in connection with a metallic 25 telephone line equipped for divided ringing, means for recording a message, means for reproducing said message, means responsive to ringing current on one side of said line for connecting said recording means to said line whereby 30 it records a message transmitted over said line, and means responsive to ringing current applied successively to said one side, then said other side and again to said one side, for connecting said reproducing means to said line for transmitting said recorded message over said line.

7. In a telephone answering and message recording system for use in connection with a metallic telephone line equipped for divided ringing, a recording and reproducing device having driving 40 means, rewind means, recording means, and reproducing means; means responsive to ringing current on one side of said line for energizing said driving means, and means for stopping said driving means after a time interval; means responsive to application of ringing current to said other side of said line for energizing said rewinding means to rewind said device, and means for stopping said rewind means; means responsive to initial application of ringing current to said one 45 side of said line and thereafter responsive to the sequential application of said ringing current to said other side and then to said one side an even number of times, for operatively connecting said recording means to said line to receive and record 50 a message on said device; and means responsive to initial application of ringing current to said one side of said line followed by sequential application of ringing current to said other side and then to said one side an odd number of times for 55 operatively connecting said reproducing means to said line to deliver a message recorded on said device to said line; whereby said device is conditioned for recording from the line in response to ringing current on one side of said line, is rewound in response to subsequent application of ringing current to the said other side of the line, and is 60 conditioned for transmitting the message recorded thereon to the line in response to subsequent application of ringing current to said one side of the line.

8. A system as described in claim 7 in which said means responsive to application of ringing current to said other side of said line for energizing said rewind means to rewind said device includes means for deenergizing said driving means 75 prior to energization of said rewind means.

9. A system as described in claim 7 in which said device is provided with normally deenergized message erasing means operatively associated with the recording and reproducing device ahead of said recording means and back of said reproducing means and in which said means for operatively connecting said recording means to said line includes means for simultaneously energizing said erasing means whereby the telephone wire is erased prior to recordation thereon. 10

10. A system as described in claim 7 in which said device is provided with normally deenergized erasing means and means for energizing said erasing means in response to initial application of ringing current to said one side of said line followed by sequential application of ringing current to said other side, to said one side, and again to said other side, whereby a message on said device is erased during rewinding thereof. 15

11. In a telephone answering system for use 20 with a metallic telephone line equipped for divided ringing; a recording and reproducing device having driving means, recording means, reproducing means, and erasing means associated therewith; means for energizing said driving 25 means and operatively connecting said reproducing means to said line in response to application of ringing current to one side of said line, means for energizing said driving means and said erasing means and operatively connecting said 30 recording means to said line in response to successive application of ringing current to the two sides of said line in a predetermined sequence, and means for restoring said system to normal condition in response to application of ringing 35 current to the two sides of said line in still another predetermined sequence.

12. In a telephone answering system for use with a metallic telephone line equipped for divided ringing; a recording and reproducing device 40 having driving means, recording means, reproducing means, and erasing means positioned ahead of said recording means and back of said reproducing means; means responsive to successive application of ringing current to one side 45 of said line for energizing said driving means and operatively connecting said reproducing means to said line following each application; means responsive to sequential application of said ringing current to said one side of said line, to the other side, and then again to said one side, for energizing said driving means and said erasing means and operatively connecting said recording means to said line; and means responsive to sequential 50 application of ringing current to said one side of the line, then said other side for a long interval, then to said one side, then to said other side for a short interval, then to said one side and then again to said other side for a long interval for restoring said system to initial condition; whereby said device delivers a message recorded thereon to said line in response to ringing current on one side of said line, whereby said device may be remotely controlled over said line to 55 erase its original message and record a new message transmitted over said line in response to the successive application of ringing current to the two sides of said line in a predetermined sequence, and whereby said device may thereafter be restored to condition for delivering the newly recorded message to said line in response to ringing current on said one side of said line, by the application of ringing current to the said other side of said line for a prolonged interval after 60 said new message has been recorded.

13. In a call answering and message recording 75

system for use in connection with a metallic telephone line equipped for divided ringing; a call answering device having driving means, recording means, reproducing means and erasing means associated therewith; a message registering device having driving means, rewind means, recording means, reproducing means and erasing means associated therewith; means selectively responsive to ringing current applied to the two sides of said line in predetermined different sequences for selectively (1) energizing said driving means on said call answering device and said message registering device, conditioning said reproducing means on said call answering device to reproduce a message thereon to said line and conditioning said recording means on said message registering device to record a message transmitted over said line, (2) energizing said rewind means associated with said message registering device to rewind the latter, (3) energizing said driving means associated with said message registering device and conditioning the reproducing means associated therewith to transmit a message recorded thereon to said line, (4) energizing said driving means on said call answering device and conditioning the erasing means and recording means associated therewith to erase an existent message thereon and record a new message transmitted over said line, or (5) energizing said rewind means on said message recording device and conditioning the erasing means associated therewith to erase a message thereon.

14. In a telephone answering and message recording system for use on a telephone line equipped for divided ringing; a call answering device; a message recording device having driving means, recording means, reproducing means and erasing means, and rewind means; relay means having a neutral, a first and a second position of operation; means for operating said relay from its neutral into its first position in response to ringing current on one side of said line and from neutral into its second position in response to ringing current on the other side of the line; a control element operable between two positions and means for operating said element into one position in response to alternate movements of said relay from its first position into its second position and for operating said element into its other position in response to intervening movements of said relay from its first position into its second position; circuit means for energizing said driving means in response to operation of said relay into its first position; circuit means for energizing said answering device and operatively connecting said recording means to said line in response to operation of said relay into its first position and operation of said control element into its one position; and means for tripping said relay into neutral position to deenergize said driving means and said answering device; whereby with said relay in neutral position and said control element in its one position said answering device is energized to signal a calling party over said line and said message recording telephone is conditioned to receive and record a message from the calling party over said line in response to the application of ringing current to said one side of said line.

15. A system as described in claim 14 in which said tripping means comprises a time switch for deenergizing said driving means and said answering device after they have run for a predetermined time.

16. A system as described in claim 14 in which

said answering device comprises a telephone having an endless record wire and in which said tripping means is actuated by said answering telephone when it completes a cycle of operation.

17. A system as described in claim 14, with means for energizing said recording device erasing means in response to operation of said relay when said control element is in its one position.

18. A system as described in claim 14 with means for energizing said rewind means in response to operation of said relay into its second position.

19. A system as described in claim 14 with means for energizing said erasing means in response to operation of said relay when said control element is in its one position and in which said means for tripping said relay is actuated in response to complete rewinding of said recording device.

20. A system as described in claim 14 with means for operatively connecting said reproducing means to said line when said control means is in its other position and said relay is operated into its first position.

21. A system as described in claim 14 in which said means for operating said first mentioned relay into its second position is a slow operating relay having slow-make contacts for completing the energizing circuit to operate said first mentioned relay into its second position only in response to prolonged application of ringing current to said other side of the line, and having fast-make contacts adapted to energize said tripping means in response to a short application of ringing current, said fast-make contacts reopening in response to prolonged application of ringing current prior to closure of said slow-make contacts.

22. A system as described in claim 14 in which said means for operating said first mentioned relay into its second position is a slow operating relay having slow-make contacts for completing the energizing circuit to operate said first mentioned relay into its second position only in response to prolonged application of ringing current to said other side of the line, and having fast-make contacts adapted to energize said tripping means in response to a short application of ringing current, said fast-make contacts reopening in response to prolonged application of ringing current prior to closure of said slow-make contacts.

40 45 50 55 60 65 70 75

23. A system as described in claim 14 in which said answering device comprises an endless recording medium having driving means, reproducing means, recording means, and erasing means; in which said circuit means for energizing said answering device in response to operation of said first mentioned relay into its first position and operation of said control element into its one position, including means for energizing said answering device driving means and operatively connecting the answering device reproducing means to said line; and in which said system further includes a transfer switch responsive to closure of said fast-make contacts while said first mentioned relay is in its first position for opening said energizing circuit for said recording device, driving means and completing the energizing circuit for said answering device driving means independent of said control element, means for energizing the erasing means and operatively connecting the recording means associated with said answering device to said line in response to movement of said control element into its said other position, and means for restor-

- ing said transfer switch to normal position in response to movement of said first mentioned relay into its second position.
23. In a telephone answering and message recording system, a message storing device having recording means and reproducing means, and means selectively responsive to telephone ringing current impulses received in predetermined sequences over a plurality of ringing channels for selectively conditioning said recording means and reproducing means either to record a received telephone message or to reproduce a message previously recorded.
24. In a call answering and message recording system for use in connection with a telephone line, a message transmitting device having record-
- ing means and reproducing means, a message receiving device having recording means and reproducing means, means selectively responsive to ringing current impulses transmitted over said telephone line in predetermined different sequences for selectively conditioning said message receiving device either to record a message received over said line or to transmit a recorded message over said line, and means selectively responsive to ringing current impulses applied successively over said line in predetermined different sequences for selectively conditioning said message transmitting device, either to record a message received over said line or to transmit a recorded message over said line.
- PAUL HENRY ROWE. 15
